(57) **CLAIM**

The ornamental design for a storage shelf, as shown and described.

DESCRIPTION

FIG. 1 is a left side elevation view of a storage shelf showing my new design, the right side elevation view being a mirror image;

FIG. 2 is a top front left elevation view thereof;

FIG. 3 is a front elevation view thereof;

FIG. 4 is a top plan view thereof;

FIG. 5 is a left side elevation view of a storage shelf showing an alternate embodiment of my new design, the right side elevation view being a mirror image;

FIG. 6 is a top front left elevation view thereof;

FIG. 7 is a front elevation view thereof; and,

FIG. 8 is a top plan view thereof.

The broken dash lines in the figures are for illustrative purposes only and represent non-claimed environmental structure. Neither the portions of the environmental structure shown in broken dash line nor the broken dash lines themselves form any part of the claimed invention.
